UNITED STATES PATENT OFFICE.

JOHN G. SODERBERG, OF WORCESTER, MASSACHUSETTS, ASSIGNOR TO CROMPTON & KNOWLES LOOM WORKS, A CORPORATION OF MASSACHUSETTS.

YARN-TUBE FRAME.

Application filed March 6, 1922. Serial No. 541,278.

To all whom it may concern:

Be it known that I, JOHN G. SODERBERG, a citizen of the United States, residing at Worcester, in the county of Worcester and

5 State of Massachusetts, have invented a new and useful Yarn-Tube Frame, of which the following is a specification.

This invention relates to a yarn tube frame of the type commonly used in certain carpet and rug looms and particularly 10 in Axminster looms.

It is the object of my invention to improve the construction of such yarn tube frames particularly by providing improved 15 means for assembling and attaching the tubes to the frame and for providing clear entrance for the yarn into the tubes.

With this general object in view, my invention in its preferred form contemplates 20 the use of a metal strip, preferably angular in cross-section, to which the yarn tubes are permanently secured, the strip having a rib or projection formed thereon adjacent the upper ends of the tubes and serving as a 25 gauge in assembling the tubes.

My invention further relates to arrangements and combinations of parts which will be hereinafter described and more particularly pointed out in the appended claim.

30 A preferred form of my invention is shown in the drawings in which—

Fig. 1 is a side elevation of a portion of a tube frame;

Fig. 2 is an end view thereof;

35 Fig. 3 is an end section taken along the line 3—3 in Fig. 1 and

Fig. 4 is an enlarged detail front elevation.

Referring to the drawings, my improved 40 tube frame comprises a bar or support 10 extending transversely of the loom and having end brackets or heads 11 which support the yarn spools 12 and by which also the frames are attached to the pattern chain.

45 A stiffening member 12^a may be provided for strengthening the frame and is shown herein as an angle iron extending beneath the frame.

50 My improvements relate particularly to the means for attaching the yarn tubes 13 to the bar 10. In the drawings I have shown the tubes 13 as permanently secured by solder or otherwise to the outer face of a metal strip or plate 14. This strip is shown 55 herein as of angular cross-section and is

provided with a rib or corrugation 15 extending longitudinally adjacent the upper ends of the tubes 13.

This rib serves as a gauge for the upper ends of the tubes when assembling the same 60 on the strip 14. The rib 15 also protects the upper ends of the tubes and guides the yarn to the tubes in such a way that the yarn cannot engage the sharp upper edges 65 of the tubes.

The bar 10 is preferably recessed along two of its edges to receive the strip 14, as clearly shown in Fig. 3, and the strip may be secured in position by fastening devices 16, also shown in Fig. 3. A single strip 14, 70 may extend the entire length of the bar 10 or the strip may be formed in sections as indicated in Fig. 1 when used on a tube frame for a relatively wide loom.

This method of assembling the tubes upon 75 the strips 14 before the latter are secured to the bars 10 presents marked advantages over the construction previously in common use, in which the bar 10 was first enclosed within a metal casing to which the yarn 80 tubes were thereafter separately secured.

Furthermore, the provision of the projection or rib 15 is of material importance in the use of the device, as it guides the yarn smoothly over the edges of the tubes and 85 prevents much breakage of yarn.

Having thus described my invention, it will be evident that changes and modifications can be made therein within the spirit and scope of my invention as set forth in 90 the claim, and I do not wish to be otherwise limited to the details herein disclosed, but what I claim is:—

A yarn tube frame comprising a bar having a longitudinally extended depressed portion, a sheet metal strip secured to said bar in said depressed portion, and a plurality of yarn tubes fixed to said strip, said metal strip having an integral longitudinally extended corrugated rib displaced outwardly 95 from its surface adjacent the upper ends of said yarn tubes and protecting the ends thereof, the tube supporting portion of said strip and the longitudinally ribbed portion thereof being disposed entirely in said depressed portion of said bar.

In testimony whereof I have hereunto affixed my signature.

JOHN G. SODERBERG.
